UNITED STATES PATENT OFFICE.

WILLIAM F. TROAST, OF LANCASTER, PENNSYLVANIA, ASSIGNOR TO THE SLAYMAKER-BARRY COMPANY, OF SAME PLACE.

PADLOCK.

SPECIFICATION forming part of Letters Patent No. 536,844, dated April 2, 1895.

Application filed September 19, 1894. Serial No. 523,505. (No model.)

To all whom it may concern:

Be it known that I, WILLIAM F. TROAST, a citizen of the United States, residing at Lancaster, in the county of Lancaster and State 5 of Pennsylvania, have invented certain Improvements in Padlocks, of which the following is a specification.

This invention relates to improvements in that class of padlocks having a vertically 10 movable shackle; and the object of the invention is to combine the advantages of the mobility of the padlock with the security of locks permanently affixed to doors.

The invention consists in the construction 15 and combination of parts hereinafter fully described, and then specifically pointed out in the claims.

In the accompanying drawings, forming a part of this specification, Figure 1 is an inner side perspective view of the body of the lock-case, the operating parts being removed. Fig. 2 is a top plan view of the same. Fig. 3 is a top plan view of the case, showing the operating parts in place locking the shackle 25 therein, and Fig. 4 a similar view, but showing the shackle extended. Fig. 5 is a vertical section on the broken line 1—1 of Fig. 4, and Fig. 6 a similar view on broken line 2—2 of Fig. 3. Fig. 7 is a plan view of the key; Figs. 30 8 and 9, plan views of two of the tumblers; Fig. 10, a bottom edge view of the lock; Fig. 11, a perspective view of the third tumbler, and Fig. 12 a side view of the shackle. Fig. 13 is a vertical section on broken line 3—3 of Fig. 4, all the mechanism excepting the tumblers being removed. Fig. 14 is a perspective 35 view of the post supporting the springs acting on the tumblers.

Similar letters indicate like parts throughout the several views.

Referring to the details of the drawings, A indicates a round case having a circular recess A' in one edge thereof to receive the hasp engaged by the lock. On the inner face of the 45 side wall A² of the lock are buttresses, a, having rivet-pins, a', projecting outward therefrom and adapted to engage corresponding openings in the closing-plate A³, which is simply a flat piece of metal having the shape of the body of the case. Adjacent to but somewhat inside of one of the jaws, A⁴, of the opening into recess A' there is a bearing a⁵, extending inward from side wall A² to said

recess, the side wall being cut away between said jaw and the bearing to permit of the entrance of the outer jaw of the bow or shackle, to be hereinafter described, and on the outer side of the inner end of bearing a⁵ is a vertical lip, a⁶, located to be engaged by the end of said shackle jaw. From and at an angle 55 with said inner end of bearing a⁵ there is a wall, B, extending back into the case and separating that side of recess A' from the adjacent portion of the interior of said case. Wall B has a wing, B', on the inner end 60 thereof forming an angle therewith and projecting beneath recess A', where it serves as a bearing for the inner jaw of the shackle. Side wall A² is also cut away adjacent to the other jaw, A⁵, of the opening into recess A', 70 as illustrated in Figs. 1 and 2, the side wall being thus cut away on both sides of the jaws of the said recess to receive the shackle.

Beneath the free end of extension B' is a post, b, that serves as a pivot for the tumblers. These tumblers, D, D' and D², are elongated vertically, and each is provided at its upper end with a dog, d, d' and d², respectively, on the side adjacent to the stem of the shackle, with a notch in the edge of which 75 they are adapted to engage. From the same end and on the side opposite the dog there projects from each tumbler a ward, e, e' and e² respectively, the second ward being widened downward below the upper ward e and, in the 80 same way, the third and lower ward e² below the second ward e'. From the lower end of each tumbler, and on the same side as the wards, there projects a locking-arm, e³, constructed to engage a recess in the key, as will 85 be hereinafter set forth. Arms e³ are of less thickness than the tumblers, being cut away on one of the horizontal faces, as illustrated in Fig. 11, that they may engage said recesses in the key, while, at the same time, the 90 shoulders e⁴ formed by this reduction in the thickness of said arms afford bearings for the springs that engage the tumblers with the stem of the shackle. These arms e³ also serve as obstacles to picking, or tampering with, the 95 lock, as the pushing upward or inward of either one of the wards by a wire or other instrument projects across the key-opening the arm e³ on the tumbler carrying that ward, or causes the arm e³ to engage said wire or other 100 instrument and prevent the complete disen-

gagement of the heel of the tumbler from the shackle, or the arm may press said wire or other instrument against the opposite wall of the key-opening while said arm itself obstructs the part, if any, of the key-opening not occupied by said wire or other instrument.

Opposite the tumblers there is a partition, E, that forms therewith a channel in which the stem of the shackle moves, said partition having an upwardly extending lip, E', on its upper end, so as to form shoulders E² near that end.

The shackle comprises a stem F having the inner end reduced to form a shoulder, f, and a head having an upper jaw F' and a lower jaw F², forming, on the side toward the tumblers, a circular opening, F³, corresponding with and adapted to register with recess A' of the case. The space between the free ends of jaws F' and F² is sufficient to permit the entrance into opening F³ of hasps of any required thickness. When the shackle is closed jaw F' engages bearing a² and lip a³, and the lower edge of jaw F² rests upon wing B'. In its movements back and forth, jaw F² slides along and against wall B, which, with the bearing of the other side of stem F against partition E, maintains the shackle in its proper position. An elongated recess, f', is cut in the back edge of stem F near its lower end, which recess is engaged by lip E' of partition E. The engagement of the upper and lower shoulders f² and f³ respectively, formed by recess f', with the opposite ends of lip E' limits the inward and outward movement of the shackle. In the edge of stem F beneath jaw F² is also formed a shoulder, f⁴, located to be engaged by the dogs of the tumblers when the shackle is locked in the case, and below shoulder f⁴ there is another shoulder, f⁵, formed in the same edge of the stem and located to be engaged by heels d³ of said tumblers when the shackle is fully in the case, whereby said shackle is locked in such position.

The edge of the shackle below shoulder f⁵ is a flat surface, so as to present a smooth bearing to the adjacent edges e⁵ of the tumblers when the shackle is moved in and out of the case. When the shackle is moved out of the case the contact with this edge thereof, in conjunction with springs g g', holds the tumblers in a stationary position.

The tumblers are forced into engagement with shoulders f⁵, and so held, by springs—one for each tumbler. These springs are wrapped around a post, G, located below the tumblers and have one end, g, of each engaging one of the shoulders e⁴ of said tumblers and the other end, g', bearing against a buttress, H, forming one of the sides of the key-opening. This buttress has two steps, h, cut in its face, each of which supports an end of one of the two upper springs g and g', while the corresponding end of the lowest of the like springs rests upon the bottom or back plate of the case, by which construction each

spring is fixed and retained in its proper position.

When freed from the engagement of the tumblers the shackle is forced upward out of the case by a spring wrapped around a post K, located between partition E and the adjacent portion of side wall A², the end I of said spring engaging shoulder f of the inner end of the shackle and end I' bearing against said partition.

The key opening L is in the lower portion of the side wall of the case and off of the center thereof. On each side of opening L and within the side wall there is a buttress H, the face of each of which forming a side of said opening being a plain, flat surface, to make a more extended bearing for the sides of the key, which is further supported and guided by a channel formed of ribs, l, extending for a portion of the distance from said opening toward the wards of the tumblers. The bottom l' of the channel is raised above the back or bottom of the case and extended beyond the inner end of said channel beneath the wards of the tumblers to wing B', serving to guide and support the key in proper position to engage said wards.

The key M is illustrated in Fig. 7. The end of the key has offsets, m, constructed to simultaneously engage the unequally extending lower edges of the tumbler wards. The position of the tumblers with reference to each other may be varied, so as to change the relative position of the wards, and the key made to conform therewith, whereby a number of locks requiring different keys can be constructed with the same tumblers; or the shape of the wards themselves may be changed. Back of the inner end the upper and lower edges of the key are cut away to form recesses, m'. These recesses are located to receive the locking arms e³ as the tumblers are disengaged from the shackle. The position of the locking arms of the different tumblers and the corresponding recesses in the key may also be varied to further guard against the surreptitious opening of the lock.

In operating, the shackle being locked in the case, the key is inserted and pushed against the wards of the tumblers, disengaging the heels d³ from the shackle, which is forced outward by spring I I'. As the key pushes the wards upward locking arms e³ engage the recesses m' of the key, which it holds in the lock until the shackle is pushed back into a position to be locked, when heels d³ are engaged with shoulders f⁵ of said shackle by the action of springs g g'. Should a key not suitable to the lock be applied to open it the first ward it engages will detach the heel of the tumbler to which it belongs from the shackle and at the same time hook its dog over shoulder f⁴, thus effectually locking the shackle in place.

I do not confine myself to any particular shape of lock-case. Neither do I restrict myself to the details of the construction and ar-

angement of parts herein shown and described, as it is obvious that many changes and alterations may be made therein without departing from the principle of my invention.

5 Having thus described my invention, what I claim as new, and desire to secure by Letters Patent, is—

1. In a padlock, the combination, with a tumbler constructed to secure the shackle in the case, of an arm formed with said tumbler and adapted to engage the key and hold the same in the case while the shackle is in an open position.

15 2. In a padlock, the combination, with a tumbler constructed to secure the shackle in the case, of a ward formed with the tumbler and adapted to be directly engaged by the key, and an arm formed with said tumbler and adapted to engage the key and hold the same in the case while the shackle is in an open position.

25 3. In a padlock, the combination, with a tumbler constructed to secure the shackle in the case, of an arm formed with said tumbler and adapted to engage behind a shoulder of the key while the shackle is in an open position, and means for holding the tumbler immovable while the shackle is in such open position.

30 4. In a padlock, the combination, with a tumbler constructed to secure the shackle in the case, of a ward formed with the tumbler and adapted to be directly engaged by the key, an arm formed with said tumbler and adapted to take behind a shoulder on the key while the shackle is in an open position, and means for holding the tumbler immovable while the shackle is in such open position.

45 5. In a padlock, the combination, with a tumbler constructed to secure the shackle in the case, of an arm formed with the tumbler on one side thereof and adapted to engage behind a shoulder of the key while the shackle is in an open position, and a heel on the other side of the tumbler bearing against said shackle, substantially as and for the purpose specified.

50 6. In a padlock, the combination, with a plurality of tumblers having dogs and heels formed therewith on opposite sides of the pivot, and wards formed with said tumblers on the sides thereof opposite said dogs and heels and constructed to be directly engaged by a key, of a shackle provided with an upper shoulder and a lower shoulder, the upper shoulder being adapted to be engaged by the dogs on the tumblers and the lower shoulder by the heels on said tumblers, substantially as and for the purpose specified.

60 7. In a padlock, the combination, with a plurality of pivoted tumblers having dogs and heels formed therewith on opposite sides of the pivot, and wards of unequal width formed with the tumblers inside of the pivot and on the sides opposite the dogs and constructed to be directly engaged by a key, of a shackle provided with an upper shoulder and

a lower shoulder, the upper shoulder being adapted to be engaged by the dogs on the tumblers and the lower shoulder by the heels on said tumblers, substantially as and for the purpose specified.

70 8. In a padlock, the combination, with a shackle, of a plurality of tumblers, a dog formed with one end of each tumbler and a heel formed with the other end of each tumbler, said dogs and heels being constructed to engage shoulders in the shackle and lock the same in the case, wards of different widths formed with the tumblers and adapted to be directly engaged by a key, and an arm formed with one of said tumblers and adapted to engage behind a shoulder in the key while the shackle is in an open position, substantially as and for the purpose specified.

75 9. In a padlock, the combination, with a shackle, of a plurality of pivoted tumblers, a dog formed with each tumbler on one side of the pivot and a heel formed with each tumbler on the other side of said pivot, said dogs and heels being constructed to engage shoulders in the shackle and lock the same in the case, wards of different widths formed with the tumblers, an arm formed with each of said tumblers and adapted to engage behind a shoulder in the key while the shackle is in an open position, and means for holding said tumblers immovable while the shackle is in such open position, substantially as and for the purpose specified.

80 10. In a padlock, the combination, with a shackle, of a tumbler having a heel thereon constructed to engage a shoulder in the shackle and lock the same in the case, a ward formed with the tumbler, and an arm formed with said tumbler below the ward and adapted to be projected in front of the key-opening as the ward is actuated to disengage the heel from the shackle.

85 11. In a padlock, the combination, with a shackle, of a tumbler having a heel and a dog thereon, each adapted to engage a shoulder in the shackle, a ward formed with said tumbler, and an arm formed with the tumbler below the ward and adapted to be projected in front of the key-opening as the ward is actuated to disengage the heel from the shackle, substantially as and for the purpose specified.

90 12. In a padlock, the combination, with a shackle, of a plurality of tumblers, a dog and a heel formed with each of said tumblers and constructed to engage shoulders in the shackle and lock the same in the case, wards of different widths formed with the tumblers, and an arm formed with each tumbler below the ward and adapted to be projected in front of the key-opening as the ward on its tumbler is actuated to disengage the heel thereof from the shackle, substantially as and for the purpose specified.
